ISAAC B. MILNE, OF TOTLEY, AND WILLIAM E. PARKER, OF SHEFFIELD, ENGLAND.

PROCESS RELATING TO THE TEMPERING OF PROJECTILES AND APPARATUS THEREFOR.

1,310,074.

Specification of Letters Patent. Patented July 15, 1919.

Application filed June 27, 1914. Serial No. 847,680.

To all whom it may concern:

Be it known that we, ROBERT ABBOTT HADFIELD, ALEXANDER G. M. JACK, ISAAC B. MILNE, and WILLIAM E. PARKER, subjects of the King of Great Britain and Ireland, all residing and doing business in England, said HADFIELD at 22 Carlton House Terrace, city of Westminster, said JACK at Rockhills, Sheffield, county of York, said MILNE at 10 Cross Grove House, Totley, county of Derby, and said PARKER at 54 Brocco Bank, Sheffield, county of York, England, have invented new and useful Improvements in Processes Relating to the Tempering of Projectiles and Apparatus Therefor, of which the following is a specification.

This invention relates to the tempering of projectiles and consists in a process and a machine, whereby, after hardening, the body portion of the projectile may be suitably and uniformly tempered, without affecting, or unduly affecting, the hardness of the head or ogival front portion.

The essential features of our process are 25 the supporting of the projectile head downwardly and immersed in water or other cooling medium, then applying heat to the body of the projectile and then permitting it to cool. Preferably the projectile is supported with its axis vertical and is rotated 30 in a suitable chamber, where its body is exposed to heat from suitable burners whereby the required tempering is effected. Desirably this heating may be effected gradually 35 in a plurality of closed chambers, and the cooling may finally take place in a special chamber.

To practice the process in a desirable manner a number of projectiles constituting a group are supported upon or conversely suspended from a movable carrier with their axes vertical and parallel to one another and with their hardened heads or ogival front end portions immersed in water 45 or other medium and their body portions exposed above the water or other medium to heating means, the group of projectiles being moved collectively through a heating chamber while each of the projectiles is simultaneously caused to rotate about its own 50 vertical axis so that the body portions of all the projectiles shall be heated to the same or substantially the same temperature for effecting the required tempering of such 55 body portions while their head portions are

kept cool after which the body portions are allowed to cool. The heating of the body portions of the group of projectiles may be effected gradually in stages and in separate heating chambers or compartments and the 60 cooling of such body portions be effected in another chamber or compartment, or the heating and cooling may be carried out in a single chamber.

The carrier supporting the group of projectiles may be mounted to rotate about a center around which the projectiles constituting the group thereof are arranged symmetrically each of such projectiles being supported in a carrier mounted to rotate 70 about the vertical axis of the projectile carried thereby and upon or in the first mentioned carrier. For maintaining the head or ogival portions of the projectiles cool during the heating of the body portions, the 75 projectile carriers may be mounted to rotate in a vessel or trough through which hot, tepid or cold water or other liquid medium is caused to flow. The heating of the body portions of the projectiles may conveniently 80 be effected by flame from a number of Bunsen or like burners opposite which the group of projectiles is caused to collectively revolve while each of the individual projectiles simultaneously revolves about its vertical axis. Conveniently three groups of projectiles may be under treatment at one time, one group undergoing a preliminary heating, a second group undergoing the final heating and a third group undergoing cooling, 85 these operations being preferably effected in separate chambers and the several groups being advanced at intervals so that the third group when sufficiently cooled is removed from the last chamber and replaced 90 by the heated second group from the second chamber the first group being then removed into the second chamber and replaced by a fresh group. In this way the tempering of projectiles can be carried out in a continuous 95 manner and under uniform conditions, so that all the projectiles will be tempered to the same extent.

Apparatus for tempering projectiles in the manner described can be constructed in 105 various forms. A desirable apparatus for the purpose is illustrated in the accompanying drawings wherein the reference characters of this description are applied to the corresponding parts in the several views. 110

Of the views Figure 1 is a horizontal sectional view of a suitable structure providing chambers wherein the projectiles are subjected to desirable temperatures. Fig. 2 is 5 a vertical cross-sectional view thereof. Fig. 3 is a cross-sectional view of the projectile carrier of our invention (section taken on line 3-3 of Fig. 5). Fig. 4 is a side elevational view at right angles to Fig. 3 with 10 portions shown in section. Fig. 5 is a plan view of the carrier with a portion broken away and Fig. 6 is an enlarged detail view of a portion of Fig. 3.

The arrangement, as shown, comprises a 15 tunnel like structure, T (hereinafter called a tunnel) composed of the supporting side walls 1-1 and the arched roof 2. The tunnel so formed at its bottom is provided with track rails 3-3 extending longitudinally 20 therethrough and it is arranged to be divided by two end and two intermediate vertically movable doors 5, into three chambers or compartments A, B and C. Preferably each door is constructed of fireclay slabs 25 fixed in a steel frame and fitted to slide in vertical slide-ways 6-6 and to that end they are supported by chains 8-8 from supporting and operating shafts 9-9 positioned above the slideways 6. The lifting chains 30 are carried by pulleys 10-10 on the shafts 9, connected at one end to the door and are provided on their opposite ends with counterbalance weights 11-11. The shafts 9 are journaled in suitably supported bearings 35 12-12 and are provided with gears 14 meshing with pinion 15 on suitably journaled operating shaft 17. On the end of the operating shaft 17 is a pulley or chain wheel 20, thus geared to rotate the shafts 9 for 40 raising or lowering of the door when rotated by an operating chain 22 indicated for that purpose. The doors, by reason of counterbalancing will remain in adjusted position.

45 Chambers A and B are heating chambers and are provided at one or at opposite sides with a number of separately controllable burners 24 adapted to burn a mixture of air and gas or oil the quantities of which are 50 capable of adjustment in the usual way, the burners being arranged in such a position as to give the best heating effect to the body portion of a group of projectiles mounted to rotate in the said chambers. Chamber C 55 is a cooling chamber. Each chamber may be open to a greater or less extent at the bottom and be provided at the upper end with outlets 4 as shown in Fig. 2 for exit of hot products of combustion or air, as the case 60 may be. Gas mains 25-25 are shown communicating with each of the burners. The openings at the bottom are provided by raising the doors 5.

65 The means for carrying and revolving each group of projectiles is best shown in

Figs. 3 to 6 and desirably comprises a stationary supporting plate or platform 30 supported horizontally within a tank 31 open at the top and carried by the bogie or wheeled vehicle 32 adapted to travel through 70 the tunnel on the track rails therein. The supporting plate 30 may be adjustable in height as shown, by being supported upon four screw studs 34 having threaded thereon supporting and clamping nuts 35-36 by 75 which the plate is held in position. The supporting plate is provided on its upper surface with an annular track or raceway 37 for bearing balls 38 arranged therein to support a main carrier plate 40. The carrier plate 40 is of annular form and is provided on its outer periphery with gear teeth 41 and is provided on its under surface with a bearing ring 42 having an annular groove therein complementary to the groove 80 of raceway 37 in forming a raceway for the bearing balls 38. An elongated driving gear 45 is arranged in mesh with the teeth 41 of the carrier plate 40. This gear is secured on a vertical shaft 46 journaled in upper 85 bracket 47 and a bearing base 48 and on the shaft is secured the worm gear 50 engaged by an operating worm 51 on a horizontal shaft 52. This latter shaft is carried by an inner bearing 53 and an outer bearing 54 90 carried by the side of the tank 31. The end of the shaft 52 is formed as a socket to receive one end of a flexible, telescopic or other suitable driving shaft which is inserted through a suitably arranged aperture 95 in one of the side walls of the tunnel when the vehicle and associated parts have been moved into the required position for the heating of the projectiles carried on the main carrier, the arrangement being such 100 that the main carrier can be rotated at the required speed which usually will be slow.

The projectiles are supported on the main carrier to be revolved about the axis thereof on rotation of the carrier and they are likewise supported whereby they are simultaneously rotated on their own axes so that the outwardly directed surfaces thereof are constantly changing. To this end each projectile J is carried on a subsidiary annular carrier 56, of which five are shown concentrically arranged, the carriers having their under surfaces grooved to co-act with annular grooves of bearing rings 58 to form annular ball races for ball bearings 59 upon 110 which the subsidiary carriers rotate. Each of the carriers 56 is of annular form and is toothed around its periphery at 60, the teeth thereof gearing into the teeth of a stationary annular toothed rack 62 secured to the supporting platform 30 by bolts 63 and spacing sleeves 64. As the annular rack 62 is concentric with the main carrier and the subsidiary carriers carried thereon, it results 115 that upon rotation of the main carrier the 120 125 130

projectiles will be revolved therewith and by reason of the constant engagement of the teeth of the subsidiary carriers with the rack the subsidiary carriers will also be caused to rotate and rotate the individual projectiles about their vertical axes.

The subsidiary carriers are suitably formed and recessed as shown, to support the projectiles in inverted position and are desirably provided with recessed ogival shaped rings 66 to fit around the ogival shaped head of an inverted projectile placed therein and extending therethrough.

Water is caused to flow in such quantity as may be desired through the tank during the heating of the bodies of the projectiles, and come in contact with the heads of the projectiles, the water being delivered into the tank, conveniently through a flexible pipe *e* passed through a hole in one of the side walls of the tunnel and extending over the edge of the tank. The overflow is through an outlet pipe *F*. (See Figs. 2 and 6.) By suitably regulating the amount of water passing through the tank in a given time any temperature of the water up to boiling point can be obtained, and in cases in which oil is used instead of water a higher temperature than the ordinary boiling point of water can be obtained to suit requirement. The depth to which the heads of the projectiles are immersed in the water can be regulated by varying the height of the overflow outlet or by raising or lowering the platform carrying the rotary carriers.

Obviously this invention is subject to various modifications without departing from the broader scope thereof.

As will be readily understood the tempering of the larger size projectile as now used presents a difficult problem to the mill operator owing to their great mass and weight, a 14" projectile being some five feet high and about a ton in weight. The arrangement herein disclosed offers a ready solution thereof and greatly facilitates the handling of these larger projectiles during tempering.

Having described our invention we claim:

1. The herein described process of tempering the body portion of a projectile which consists in supporting the projectile with its point immersed in a cooling liquid and subjecting the body and entire remaining portion of the projectile to a heating and tempering temperature while the point is so protected.

2. The herein described process of tempering projectiles which consist in supporting the projectiles with their points immersed in a liquid cooling medium, subjecting the exposed body of the projectile to heating temperatures and rotating the projectiles so positioned during the heating thereof.

3. The herein described process of temper-

ing projectiles consisting in arranging the projectiles in a suitable carrier with their points immersed in a cooling medium, subjecting the exposed portions of the projectiles to a heating means while so supported and rotating the carrier constantly to change the position of the projectiles relative to the heating means to effect uniform heating thereof.

4. The herein described process of tempering projectiles consisting in arranging a series of projectiles in a suitable carrier with their points immersed in a cooling medium, positioning the carrier with the projectiles so supported in a heating chamber to be subjected to the influence of heating means therein and rotating the projectiles with relation to the heating means for the uniform heating thereof.

5. The herein described process for tempering projectiles consisting in arranging a series of projectiles in a suitable carrier with their points immersed in a cooling medium and positioning the carrier in successive chambers for subjecting the exposed portions of the projectiles to the temperatures thereof while maintaining the points immersed in the cooling medium.

6. The herein described process for tempering projectiles consisting in arranging a series of projectiles in a suitable carrier with their points immersed in a cooling medium, positioning the carrier in successive chambers in the presence of a heating means therein and rotating the carrier constantly to change the position of the projectiles relative to the heating means to effect uniform heating thereof.

7. A carrier for projectiles comprising a supporting truck, a tank supported thereon for containing a liquid cooling medium and a projectile supporting member arranged within the tank and adapted to support projectiles with their points immersed in the cooling medium.

8. A carrier for projectiles comprising a supporting truck a tank supported thereon for containing a liquid cooling medium, a projectile supporting member suitably journaled in the tank and adapted to support projectiles with their points immersed in the cooling medium and means to rotate the supporting member.

9. A carrier for projectiles comprising a supporting truck a tank supported thereon for containing a liquid cooling medium, a supporting member supported to be vertically adjustable within the tank, bearings on the supporting plate, a main carrier rotatable on the bearings, means to rotate the main carrier, driving connections thereto extended externally of the tank, supports for the projectiles journaled on the carrier and means operative to rotate the supports upon rotation of the main carrier whereby

- the projectiles will simultaneously be revolved and rotated about their individual axes.
10. A carrier for projectiles comprising a supporting truck a tank supported thereon for a liquid cooling medium, a stationary supporting plate supported to be vertically adjustable within the tank, bearings on the supporting plate, a main carrier rotatable on the bearings, a peripheral gear on the main carrier, a driving gear in engagement therewith to rotate the main carrier, driving connections thereto extended externally of the tank, supports for the projectiles journaled on the carrier in concentric arrangement and provided with gear teeth on their outer peripheries and a stationary annular rack supported concentric to the mutual axis of the supports and to be constantly engaged by the gear teeth of the supports whereby they are rotated about their individual axes.
11. The herein described process of tempering the body portion of a projectile after hardening without affecting or unduly affecting the hardness of the head or point, which consists in first hardening the entire projectile, and then supporting the projectile with its point arranged downwardly and immersed in a cooling liquid and subjecting the body and entire remainder of the projectile to a heating and tempering temperature while the point is so protected.
12. Means for tempering projectiles comprising a series of chambers, means for heating the same, a continuous track passing through the chambers, a truck to run on said track, a tank on said truck, a carrier in the tank for a plurality of projectiles, means to rotate the carrier, annular supports one for each projectile on the carrier, means to rotate said supports and means to elevate and depress the carrier at varying heights in the tank.
13. The herein described process of uniformly tempering the bodies of projectiles which consists in supporting the projectiles with their points immersed in a cooling liquid and their bodies unprotected, moving the projectiles onwardly through a heating furnace, and while so moving the projectiles onwardly, moving them from side to side in the furnace and rotating each projectile and finally cooling in a special cooling chamber.
14. The herein described process of uniformly tempering the bodies of projectiles after hardening without unduly affecting the hardness of the head, which consists in first hardening the projectiles, then supporting them with their points immersed in a cooling liquid and with their bodies exposed, moving them through a heating chamber or chambers, giving them a secondary and lateral motion while passing through the chamber, and also rotating each projectile while so passing, and finally cooling in a special cooling chamber.
15. The herein described process of uniformly tempering the bodies of projectiles after hardening without unduly affecting the hardness of the head, which consists in supporting the projectiles with their points immersed in a cooling medium, moving the projectiles through zones of different degrees of temperature, and rotating each projectile while so moving to expose the entire surface to the direct action of the heat, thereby to insure uniform heating of the projectile body, and finally cooling.
16. The herein described process of tempering projectiles which consists in supporting a group of the same on a suitable car, each being supported independently on a suitable rotatable support on said car, moving the car through a chamber or series of chambers to heat and then cool the projectiles, and while so moving the car, rotating the entire group of projectiles and rotating each projectile independent of the others.
17. The herein described process of tempering projectiles which consists in supporting the same on a suitable car, point downwardly and with their points immersed in liquid, each projectile being supported independently on a suitable support on said car, moving the car through a chamber or series of chambers, gradually to heat and then gradually to cool the projectiles, rotating the entire group of projectiles as the car is so moving and simultaneously rotating each projectile independently of the others.
18. The herein described process of tempering projectiles which consists in supporting the same on a suitable support with the axes of all vertical and parallel, each being carried independently on a suitable rotatable standard on said support, and each being arranged with point down and immersed in hot, tepid or cold water flowing through a suitable trough, moving the support through a chamber or series of chambers to heat and then cool the projectile bodies, and while so moving the support, rotating the entire group of projectiles and rotating each projectile independently of the others, substantially as described and shown.
19. The herein described process of tempering the body portion of a hardened projectile without reducing the hardness of the pointed front end portion of the projectile which consists in supporting the projectile point downward with its pointed front end portion immersed in a cooling liquid, subjecting said body portion of the projectile to a suitable heating and tempering temperature, afterward partly reducing the temperature of the said body portion to a suitable degree and then removing it from the

cooling zone, substantially as described and shown.

20. The herein described process of tempering the body portion of a hardened projectile without reducing the hardness of the pointed front end portion of the projectile, which consists in supporting the projectile point downward with its pointed front end portion immersed in a cooling liquid, subjecting said body portion of the projectile to a suitable heating and tempering temperature, afterward slowly cooling the said body portion and when cooled to the desired degree, removing it from the cooling zone, substantially as described and shown.

21. The herein described process of tempering the body portion of a hardened projectile without reducing the hardness of the pointed front end portion of the projectile, which consists in supporting the projectile point downward with its pointed front end portion immersed in a cooling liquid, subjecting said body portion of the projectile to a suitable heating and tempering temperature, afterward slowly reducing the temperature of the said body portion of the projectile and removing it from the cooling zone while still heated, for completing its cooling by quenching it in a cooling medium outside the cooling zone substantially as described and shown.

22. The herein described process of tem-

pering the body portion of a hardened projectile without reducing the hardness of the pointed front end portion of the projectile which consists in supporting the projectile point downward with its pointed front end portion immersed in a cooling liquid, subjecting said body portion of the projectile to a suitable heating and tempering temperature, afterward slowly reducing the temperature of the said body portion of the projectile and removing it from the cooling zone while still heated, for completing its cooling by quenching it in a cooling medium outside the cooling zone substantially as described and shown.
